METHOD AND MEANS FOR CURLING HAIR

Virginio Jean Gentile, Summit, N. J.

Application May 11, 1933, Serial No. 670,459

24 Claims. (Cl. 132—36)

The invention relates to a novel and useful method and means for curling or winding hair and more particularly to such method and means for automatically winding curls on the human head in the process of permanent waving.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is an elevation of a winding mechanism and stand embodying the invention, parts being broken away to show the interior of the stand;

Fig. 2 is an elevation of a completed curl on the human head as produced by the invention;

Fig. 3 is a fragmentary elevation showing the starting of a curl;

Fig. 4 is an enlarged longitudinal central section of a preferred form of the winding mechanism;

Fig. 4a is a continuation of Fig. 4 showing the winding end of the device;

Fig. 5 is a fragmentary elevation of the winding head showing a partially wound curl;

Fig. 6 is a fragmentary top plan of the winding head;

Fig. 7 is an elevation on a smaller scale of the winder, showing the preferred form of tape-supply means;

Fig. 8 is a top plan of Fig. 7;

Fig. 9 is a section taken on line 9—9 of Fig. 8;

Fig. 10 is a side elevation of the winding head opposite to that shown in Fig. 5;

Fig. 11 is a top plan taken on Fig. 10;

Fig. 12 is a cross-section on line 12—12 of Fig. 4;

Fig. 13 is a section on line 13—13 of Fig. 4;

Fig. 14 is a section on the broken line 14—14 of Fig. 4a;

Fig. 15 is an elevation of the guide nut shown in Fig. 4;

Fig. 16 is an end elevation of the winder as seen from the left in Fig. 4a;

Fig. 17 is a fragmentary longitudinal section

of the driven head of the guide barrel with the pilot rod broken and the guide nut removed;

Fig. 18 is a longitudinal elevation similar to Fig. 7, but showing one modified form of tape-supply means;

Fig. 19 is a top plan of Fig. 18;

Fig. 20 is a detail perspective enlargement of a tape guide;

Fig. 21 is a perspective view of a tape clip;

Fig. 22 is a fragmentary enlargement of the winder barrel and tape-supply means shown in Fig. 18;

Fig. 23 is a section taken on line 24—24 of Fig. 22, but showing the tape casing cover open;

Fig. 24 is a section on line 24—24 of Fig. 22;

Fig. 25 is a detail perspective view of the base of the tape casing shown in Fig. 22;

Fig. 26 is a similar perspective view of the lid for said tape casing;

Fig. 27 is a similar perspective of a plicated bale or charge of tape;

Fig. 28 and Fig. 29 comprise a central longitudinal section of a modified form of winder-guiding means and tape supply;

Fig. 30 is a longitudinal side elevation of the mechanism shown in Fig. 28;

Fig. 31 is a detailed perspective view of a reel of tape and a holding clip therefor;

Fig. 32 is a section on line 32—32 of Fig. 30;

Fig. 33 is a partial longitudinal section of a modified form of winder;

Fig. 34 is a section on line 34—34 of Fig. 33;

Fig. 35 is a fragmentary elevation similar to Fig. 5, showing the hair-smoothing brush; and

Fig. 36 is a view similar to Fig. 14, showing the brush.

The invention provides a new, improved, very efficient and simple method and means for winding, coiling or curling living hair on the human head preparatory to the steaming and dressing thereof in the process of permanent waving. By the invention it is possible to wind growing tresses upon permanent waving mandrels or curling rods with great speed, accuracy, precision and uniformity. The curls produced are tighter, stronger and more shapely and symmetrical than any which can be produced manually by the most skilled hairdresser, while the speed and uniformity of winding cannot be approached by hand methods nor by any known device for facilitating manual winding.

The invention eliminates the need for the services of highly skilled hairdressers in the winding or curling of the hair and also precludes the possibility of faulty and non-uniform results due to

human inaccuracy and lack of skill and/or strength in the hair-winding operation. By the invention the hair is wound entirely automatically in a mechanically predetermined form which is perfectly symmetrical and technically correct from the hairdressing standpoint. The invention not only reduces the hair-winding operation to a purely mechanical step, but the curls produced thereby are actually technically superior and more beautiful than any which can be produced by the most careful and skillful manual winding.

Nevertheless, the hairdresser is not deprived from exercising his individual skill, experience and artistry because his judgment in "squaring off" the head (i. e. determining the quantity of hair to be wound in each tress) and his knowledge of the nature and texture of the hair to be treated are still exercised to the full. In fact, the invention provides superior facilities for reducing the onerous and routine steps of the hair-waving process to a minimum, thereby freeing the hairdresser to employ his time and thought in treating the individual problems of the particular hair being waved. The invention very greatly reduces the time and labor required to curl a head of hair, the winding operation being wholly mechanical, as stated, and therefore requiring substantially no exertion, skilled manipulation or careful regulation on the part of the operator. The time consumed in curling a head of hair is but a small fraction of that required by manual methods, while the comfort and safety of the customer and the profits of the hairdresser are proportionately increased.

The invention provides a method and means whereby the hair-winding operation can be performed with maximum accuracy, efficiency and safety by comparatively unskilled operators. An especially important object of the invention is to provide an automatic hair-winding method and mechanism which is entirely safe, fool-proof and comfortable. It is impossible for the device embodying the invention to twist, pull or entangle the hair in spite of the fact that the hair-winding means is positively driven by an electric motor drive at about 250 R. P. M. A tress is rapidly and automatically curled or wound around a curling rod or mandrel fastened to said tress near the scalp, but the curling rod is locked or positively prevented from turning with the winding means so that no twisting movement can be imparted to the rod nor the roots of the hair by said winding means. Furthermore, the winding movement can be maintained only by conscious and positive control of the operator so that the machine automatically stops whenever the operator releases his controlling grip. These safety features not only protect the customer from injury, but add greatly to her comfort and peace of mind.

A further object of the invention is to provide a method and means for automatically and positively binding the wound hair to the curling rod throughout the length of a curl. The hair is tensioned, wound and pressed tightly against the curling rod in a smooth, continuous and positive movement and is immediately bound tightly in place by a following binder, such as a strip of tape or the like which is likewise tensioned and pressed against the wound tress by the automatic winding means. The overlapping and binding action of the tape prevents the ends of the individual hairs from straying and springing out of place.

so that the entire curl is automatically maintained in its wound form.

The invention provides an improved method and means for supplying the binding tape or strip for the individual curls during the winding thereof. The binding tape is fed from a substantially continuous supply thereof, which is carried by the winding mechanism, whereby the winding device is equipped with sufficient tape to easily wind all the tresses upon a head having more than the average amount of hair. Tape shearing means are also provided for severing lengths of tape from the continuous supply after a length thereof has been wound upon a curl.

The present preferred embodiment of the invention broadly comprises hair-engaging and guiding means adapted to successively wind tresses helically about individual, interchangeable curling rods or mandrels attached to the tresses near the scalp of the customer. The individual tress is wound from its root end outward about its respective curling rod, the hair-engaging means automatically wrapping the tress around and along the rod with a continuous movement. The hair is wound under predetermined tension so as to give it the desired stretch and the stretch and tension are preserved throughout the length of the curl by pressing the stretched hair tightly against the curling rod and binding it with tape as herein-after described. Each curl is wound in conformity to a standard guide having a technically predetermined helical configuration, the pitch of the helix being varied to compensate for the decreasing thickness of the tresses toward their outer ends. However, the device is also capable of selective operation independently of the fixed guiding means, whereby all or a portion of the curl may be wound in a coil having its pitch manually controlled by the operator, thereby to vary a part or all of the curl configuration from that of the standard fixed guide.

The curled hair is automatically wrapped or bound with a binding strip of tape or other suitable binding material. As hereinbefore described, the tape overlaps the turns of hair on the rod, thereby binding down any stray ends of the shorter hairs which might tend to escape from the wound tress intermediate its ends. The binding tape is subjected to the same tension and pressure as the hair itself and thereby conforms intimately to the outer surface of the wound curl. Said tape is preferably supplied from a substantially continuous supply source mounted on and traveling with the hair-winding means, the quantity of tape carried by the winding means being more than sufficient to wind all the tresses in the average head of hair. The winding device is provided with suitable guides for leading the tape to the point of application on the curl and with a cutter for shearing the tape after a curl has been wound.

In accordance with the invention, the hair-guiding and winding means is preferably rotated automatically about the curling rod or mandrel by a motorized drive. Briefly, a flexible shaft, driven from a motor, is connected to a driving gear located in that part of the winding device held in the hand of the operator. A hand-operated clutch connects the driving gear to a driven gear on the rotating part of the winder thereby to impart the desired rotary movement. The clutch is adapted to operate only when positively actuated by the operator, being normally urged to its disconnected position by spring means.

The embodied means for preventing turning of the curling rod with the winding means during the winding operation comprises a pilot rod or key which engages the hollow interior of the 5 interchangeable curling rods. Said pilot rod preferably has a non-circular cross-section which coacts with the similarly shaped interior of the hollow curling rod. The pilot rod is keyed or otherwise fixed to a non-rotating part of the 10 winding mechanism, such as the clutch body, which is held stationary in the hand of the operator. By virtue of the construction described, the curling rod and the hair roots attached thereto are prevented from receiving any twisting or 15 pulling movement from the rotating part of the winding mechanism, thereby obviating harm or discomfort to the customer. In actual practice the winding operation is far more comfortable and safe than the best hand wind because the 20 winding motion is absolutely steady, continuous and it cannot twist or pull the hair or scalp.

In operation the winding device is successively connected to the various curling rods which are attached to the various tresses in the head of 25 hair in order to curl a tress about its curling rod and is detached from the curling rod when the curl is completed, bound with tape and the tape severed from the wound length. The winding device is thus rapidly and successively connected 30 to the various curling rods which cooperate as part of the winding mechanism during the winding of their respective curls.

The present invention is an improvement on the method and means for curling hair disclosed 35 in my prior co-pending application Serial No. 467,530, filed July 12, 1930.

It will be understood that the foregoing general description and the following detailed description as well are illustrative and exemplary 40 of the invention but are not restrictive thereof. Various features of the invention are susceptible of considerable modification while retaining the basic principles thereof, some of such modifications being disclosed herein and others of which 45 will be obvious to those skilled in the art.

Referring now in detail to the present preferred embodiment of the invention, illustrated by way of example in the accompanying drawings, a separate rigid curling rod or mandrel 50 1 (Figs. 2, 3, 4, 4a) is provided as a core for the winding of each tress in the head of hair to be permanently waved. As embodied, the major portion of the rod is a hollow cylinder having a smooth uniform exterior and an outside 55 diameter of about one-fourth inch. In the preferred form, the cylindrical portion 1 of the rod is preferably provided with a non-circular and preferably square bore 2 (Figs. 4 and 13), said square bore being adapted to cooperate with the 60 winder pilot rod as hereinafter described. The hollow curling rod may also be perforated throughout all or a portion of its length, as and for the purpose disclosed in my co-pending application Serial No. 634,097 filed September 21, 65 1932.

Means are provided for securely fastening a tress to the lower or scalp end of the curling rod 1 and for facilitating the starting of the curl thereon. As shown, the lower end of the rod is 70 tapered to provide a shank 3 of gradually decreasing cross-section. Said tapered shank facilitates starting of the curl about the rod and provides a curl of more uniform exterior diameter, the decrease in diameter of the rod compensating 75 for the greater thickness of hair near the scalp

end of the tress. The means for fastening a tress to the end of the rod near the scalp comprises a head 4 having a hair-retaining shoulder 5 which justs fairly abruptly from the reduced end of the shank 3. A narrow slot or notch 6 extends axially 5 of the head 4 to provide means for securing a piece of string or the like to the rod, thereby to tie the hair firmly and easily to the end of the rod as indicated in Fig. 3. The head 4 may be flattened as shown and provided with curved indentations 7 10 to facilitate gripping of the hair thereon, or if desired, the head may be a slotted cylindrical member. Preferably, the tapered shank 3 of the rod is hollow down to or near the end thereof.

In utilizing the invention, it will be understood 15 that a number of curling rods or mandrels of the construction hereinbefore described will be provided and attached individually to the various tresses on the "squared off" head. Thereafter, the tresses will be wound about their respective curling rods by the winding mechanism hereinafter described. Referring now to the embodied means for winding a tress helically from its root end 20 outwards about the attached curling rod 1, said means can be conveniently classified into several 25 major sub-groups of mechanisms as follows:

(a) The hair engaging head, comprising devices for slidably gripping and tensioning the hair and pressing it against the curling rod.

(b) Mechanism for guiding the hair-engaging 30 head along and about the curling rod in a predetermined helical path, comprising the grooved guide barrel, the guide-engaging nut and the non-rotating pilot device.

(c) Mechanism for driving or rotating the 35 winder.

(d) Mechanism for wrapping the wound tress with a binding strip of tape or the like. In the following description, the various sub-groups of mechanisms will be described in the order given. 40

A.—The hair-engaging head

Means are provided for engaging or frictionally gripping the free portion of the tress to wrap or wind same around and about the curling rod. 45 As embodied, said means comprise two principal hair-engaging members for slidably gripping and pressing the hair as it is wrapped about the mandrel, said members being fixed to a block or head 16 which is rotated along and about the mandrel 50 in a predetermined helical path as hereinafter described. One of said principal hair-engaging members comprises the pivotally mounted presser foot 18 which has a hair-engaging and smoothing face 11 adapted to lie resiliently against the 55 periphery of the curling rod 1 when same is mounted in the winding mechanism. The hair-engaging face 11 is suitably curved to overlie and press down the tress as it is being wound about the curling rod. The hair-engaging presser foot 18 has a compound yielding movement with respect to the curling rod and the hair being wound thereupon. As shown in Fig. 4a, the member 18 comprises a hollow block which is pivotally mounted at 12 on one arm 13 of a lever 14. Said 60 lever 14 is pivotally mounted at 15 in the main block 16 of the winder head, the latter being suitably recessed as shown in Fig. 4a to receive pivot 15 and the portion 18 of the L-shaped arm 17, 65 18 of the lever 14.

The arm 13 of lever 14 is spring-urged so as to force the presser foot 18 toward the hair on the curling rod. As shown, arm 17 of the lever 14 projects along the winder at a small angle to the axis thereof so as to provide an 70 75

actuating handle for the presser foot. The means for exerting spring pressure on the lever comprises a plunger 20 mounted in a barrel 21 which extends axially from the block 16 of the winder head. A suitable helical spring 22 lies within the barrel 21 and the hollow plunger 20, thereby urging the plunger outwardly or toward arm 18 of the lever. The outward end 23 of the plunger engages a shoulder 24 on the arm 18 of the lever 14, said shoulder thereby having a sliding and rocking movement with respect to the face 23 of the plunger. It will be clear that the plunger normally forces the member 18 toward the curling rod 1, but that the presser foot 10 may be moved 15 away from the curling rod by depressing the handle 17 of the lever 14. Accordingly, the presser foot 10 has a major pivotal movement toward and away from the curling rod by virtue of its mounting on the arm 13 of lever 14. In Fig. 20 4a the handle 17 is shown partially depressed.

In addition to the major pivotal movement described, the hair-presser foot 10 has a minor pivotal or rocking movement with respect to the curling rod, thereby making said presser foot 25 substantially self-aligning or self-adjusting with respect to the surface of the curling rod in order that the presser foot may conform intimately to the thickness of the hair beneath it on the rod. Arm 13 of the lever is recessed at 27 and 28 on 30 either side of the pivot 12 and helical springs 29 are mounted in said recesses. The projecting ends of said springs lie against the opposite inner face 30 of the hollow member 18, thereby providing a resilient three-point mounting of said member 18 with respect to the arm 13 of the lever. It will be clear from the foregoing that the curved face 11 of presser foot 10 is urged toward the hair on the curling rod, but that said face 11 is capable of self-adjustment with respect to 40 the hair beneath it so that a very intimate and complete sliding pressure may be exerted upon the hair and against the curling rod.

The curve of face 11 of the presser foot 10 is such that the hair is both urged and smoothed 45 against the curling rod as it is wrapped thereabout. As will be clear from Figs. 14 and 16, the rounded face 11 is provided with a trailing edge 34 which tends to follow and hug the hair and give it a final smoothing and pressure.

50 Means are provided for guiding the hair to the presser foot 10 and for concurrently subjecting said hair to a stretching or tensioning action. As embodied, a guide member 40 extends axially from the block 16 of the winder head, preferably diametrically opposite to the presser foot 10. A relatively short and deep hair-guiding groove 41 (Fig. 5) is provided in the outer face of said member 40, said groove extending at a slight angle to the axis of the member 40, thereby to guide the hair on to the curling rod 1 at the proper angle for effecting the desired overlapping helical wind of the tress. The hair is confined in the groove by the up-standing sides thereof which form a flange or shoulder 42 at the end of member 40 and a similar shoulder 43 along a median section of the member 40. The bottom of the groove 41 is suitably curved to impart the desired smoothness of travel and angle of approach to the hair as it is wound on to the curling rod. The member 40 may be fixed to the head block 16 by binding screws 44, as shown in Fig. 5, or it may comprise an integral portion of said head block 16.

Means are provided for suitably compressing, tensioning and stretching the hair as it passes

through the guide groove 41 and on to the curling rod 1. As embodied, a hair-tensioning roller 48 is provided for compressing the hair against the bottom of guide groove 41. Said roller is preferably constructed of relatively soft and yielding material, such as sponge rubber, which will give a gripping and compressive action very similar to that of the human fingers.

Means are provided for normally urging the roller 48 against the tress as it lies in the groove 10 41. Said means are also adapted to permit bodily removal of the roller from the guide groove 41 so that the tress may be inserted into the guide groove preparatory to winding. As embodied, the tension roller 48 is carried by a movable 15 arm 50, said arm being pivotally mounted in the winder head 16 by the pivot pin 51. A suitable axial channel 52 for receiving the roller and arm 50 extends through head member 16 and the length of member 40, the flange 42 being suitably recessed as shown in Fig. 16. The embodied means for resiliently urging roller 48 towards the bottom of guide groove 41 comprises a spring plunger 55 which bears against the short bevel end 56 of roller arm 50. Said spring plunger 55 25 is substantially identical in construction with plunger 20 hereinbefore described. As indicated in dotted lines in Fig. 5, the roller arm 50 may be lifted bodily out of its channel 52 and snapped into a radially-extending position. The end of 30 plunger 55 will then bear against the face 57 of arm 50 and will tend to maintain the arm extended in said radial position as the dotted lines indicate. When the roller arm 50 is pushed toward the guide groove 41, the beveled end 56 35 causes the roller arm to snap into the position shown in Fig. 4, in which position the spring plunger 55 tends to hold it.

Supplemental means are provided for resiliently urging the roller 48 at a predetermined angle 40 against the hair in the guide trough 41, whereby the hair will be maintained at the desired angle of feed and the tensioning and feeding means will adapt themselves to the quantity and thickness of hair in the tress. As embodied, the roller 45 48 is pivotally mounted within the roller arm or housing 50 and is provided with spring means for urging the roller toward the guide groove 41 at the desired predetermined angle. The roller is rotatably journaled in a U-shaped cradle 60, 50 said cradle being pivotally mounted at its center on the pin 61 so as to have a rocking movement within the hollowed out portion of roller arm 50. The outer end of roller 48 is spring-urged toward the bottom of guide groove 41 by helical spring 55 62 seated in a recess 63 in the cradle 60 and bearing against the inner face of the roller arm 50. This construction causes the outer end of roller 48 to bear against the guide groove 41 with relatively greater force than its inner end, thereby 60 tending to keep the tress against shoulder 43 and at the predetermined feeding angle as indicated in Fig. 5.

It has been found in practice that a roller, covered with rubber or similar resilient material 65 and mounted as shown, provides a smoothing, compressing, tensioning and compacting action which is exceedingly efficacious in winding the hair. However, other devices may be used, as for example, a pad of sponge rubber having no 70 rotary motion has been found to be very effective and it will be understood that various other modifications and equivalents may be provided in lieu of the preferred form here shown.

Means are optionally provided for combing and 75

evenly spreading the hair as it is drawn into the guide groove 41 and beneath the tensioning roller 48. Such means preferably comprise a line of comb teeth 65 at the mouth of guide groove 41. 5 These comb teeth straighten out any snarls in the tress just before it is tensioned and wound on the curling rod. Furthermore, the teeth 65 provide means for distributing the tress within the guide groove 41 so that a tress may be 10 bunched into a part of the guide channel or spread uniformly thereacross as desired or as required by the thickness of the tress and/or the characteristics of the hair.

A further means for maintaining the smoothing tensioning and guiding action on the hair is shown in Figs. 35 and 36. As embodied, the preferred form of the mechanism comprises a flexible hair smoothing device such as a brush having bristles 66 which are adapted to lie against the 15 tress as it is fed from the guide groove 41 and on to the curling rod 1 beneath the face 11 of the presser foot 10. Said bristles are mounted in a brush frame 67 which is swiveled on the block 10 of the presser foot and extends therefrom so 20 that the curved end 68 lies opposite the curling rod 1 and directs the bristles between it and the presser foot. As shown in Fig. 35, the tress passes between the bristles and the curling rod before it reaches the presser foot. Accordingly, the 25 bristles of the brush smooth down and follow the hair and prevent any stray ends from springing up and escaping or "creeping" out of the general line of the curl. The pressure of the presser foot against the bristles causes them to spread 30 out and mingle with the hairs of the tress, thereby providing a pressing surface which conforms intimately and flexibly to the surface of the tress and which serves to hold and guide the short ends of the hair at that point. This feature of 35 the invention is of great importance because it causes every hair in the curl to maintain the desired configuration imparted to it by the winder and the tensioning roller. The hair is thus held in exactly the desired feed angle as it travels 40 from the roller until it is caught and bound by the tape, as hereinafter described.

B.—The winder-guiding means

The invention provides means for guiding the 50 hair-engaging head hereinbefore described in a predetermined helical path along and about the curling rod, thereby to wrap or wind the hair on the rod in a curl having the desired configuration. As embodied, the winder head block 16 is 55 fixed to a relatively long cylindrical tube or barrel 70 having a helical guiding groove 71 cut in the inner surface of its wall throughout the greater part of the barrel length. The lower part of the barrel 70 (i. e. the part adjacent the head 60 16) is of greater interior diameter than the grooved part 71, being adapted to fit over the cylinder 72 projecting from the head block 16. The barrel 70 is fixed to head block 16 by a tight 65 press fit on to the head cylinder 72 and seats against an annular shoulder 73 in the block 16. A set-screw 74 (Figs. 5, 6, 10 and 11) may be provided for securing the barrel 70 to the head cylinder 72.

As will be clear from Figs. 4a and 14, the head 70 block 16 is provided with a central cylindrical opening 75 for permitting free entry of the open end of curling rod 1. A ballbearing 76 is mounted just within the opening 75 so as to form a rotatable bearing fit between the surface of the 75 curling rod 1 and the interior face of head cyl-

inder 72. As shown, the retaining ring 77 of the bearing is seated on the shoulder formed between the main body of block 16 and the head cylinder 72.

As already stated, the relatively long and thick portion of barrel 70 is provided with a helical winder-guiding groove 71 cut in the interior face of the tube wall. As shown, said guide groove 70 varies constantly in pitch (i. e. the number of turns per unit length) from one end to the other. 10 This variation in pitch is to compensate for the gradually decreasing thickness of a tress toward its outer end. The guide groove 71 causes the winder head to travel in a path having the configuration of the groove itself and thereby to 15 wind the hair in a curl having said configuration. Accordingly, the groove causes the curl to be wound in a relatively wide helix near the scalp while the curl becomes more and more nearly circular as the wind approaches the end of the 20 curl where the hair is relatively thin. The final or bottom turn 80 of the guide groove is circular, so that the ends of the tress may be wound in a complete circle upon themselves about the 25 curling rod. This construction insures that the end of the tress will be completely wrapped about the curling rod regardless of the tress length, as the end portion of the tress may be given as many 30 circular turns as are required. This construction also provides the tresses with tight ringlet 35 ends which are so desirable in hairdressing and which ordinarily can not be made with the usual helical winding.

The invention provides means for holding the curling rod 1 from turning with the barrel 70 35 and the hair-winding head as they rotate. As embodied, a pilot rod 81 is mounted axially of the barrel 70 and extends the length thereof. The end 82 of said rod is mounted so as to hold the rod stationary with respect to the rotatable barrel 70 as hereinafter described under section "C", so that the pilot rod 81 forms a fixed axis about which the barrel and winding head may rotate. The pilot rod 81 is square in cross-section and is adapted to fit slidably within the curling rod 40 45 1 (Fig. 13). The free or unsupported end 83 of said rod is tapered to facilitate entry thereof into the open end of the curling rod. It will be clear that the pilot rod acts to restrain the curling rod 45 50 55 1 from rotating, while the winder barrel 70 and winder head 16, etc. may rotate freely about the curling rod. However, the pilot rod permits free axial movement with respect to the curling rod. It will be understood that the pilot rod and bore of the curling rod may have other non-circular cross-sections than the square shape shown, the purpose of said construction being merely to prevent relative rotation of said members.

Means are provided for effecting the desired cooperation and guiding action between the 60 curling rod 1, the pilot rod 81 and the helical guide 71 hereinbefore described. As embodied, a guide-engaging follower or finger 88 is adapted to engage in the helical groove 71, thereby to force the barrel 70 and the winder head 16, etc. 65 to travel in a helical path when rotary movement is imparted to the barrel. Said follower 88 is adapted to co-act mechanically with the open end of the curling rod 1 in effecting helical movement of the barrel and winding head with respect 70 to the curling rod. As embodied, the follower 88 extends radially from the end of pivoted latch 89. The latch is pivotally mounted on a pin 92 within a recess 91 formed in cylindrical nut 90. The latch normally lies wholly within said re- 75

cess so that the end of follower 88 is flush with the periphery of the nut and the latch is held in said retracted position by a leaf spring 92a which lies in an annular groove extending part way around the nut and which forces the latch inwardly (Fig. 15).

The nut 90 is mounted for axial sliding movement on pilot rod 81 and is provided with a square bore 95 which fits slidably on the square pilot rod. The nut has an outer diameter slightly less than the interior of barrel 70 and is thus adapted to travel the length of the barrel 70, but is prevented from rotating therewith by its engagement with the pilot rod.

As stated, the nut is adapted to engage the open end of the curling rod 1 when same is inserted into the barrel. Accordingly, the nut is counter-bored at 96 to provide a cylindrical recess for slidably receiving the end of rod 1. Engagement of the rod 1 with the nut is adapted to effect guiding cooperation between the curling rod and the helical groove 71. As embodied, latch 89 is provided with an inwardly projecting dog or tongue 97 which is adapted to be forced outwardly by introduction of the end of the curling rod. As shown in Fig. 4, when the end of the rod is introduced into the recess 96, it first encounters the beveled face of dog 97, thereby causing latch 89 to rock gradually outwardly against the spring 92a. When the end of the curling rod is fully seated in the recess 96, the latch 89 will have been forced outwardly sufficiently to cause complete engagement of the follower 88 in the helical groove 71 and then the dog 97 will firmly grip the end of the curling rod.

It will be clear that the dog 97 of the nut will engage the end of the curling rod only when the latter can be shoved home into the recess 96. Accordingly, initial engagement of the curling rod and the nut is normally effected only when the nut has been stopped by the face 98 at the end of barrel 70. In that position the curling rod can be shoved home and the follower 88 will automatically engage in the first turn of the helical groove 71. In Fig. 4 and Fig. 4a the parts are all shown in assembled position, with the curling rod having just been inserted into the nut. In this position the head 4 of the rod projects just beyond the ends of the winding-head members 10 and 40, so that the rod is in position for receiving the first lap of the tress, as indicated in Fig. 3.

It will be noted further that the initial turn 99 of the helical groove is substantially circular, that is, it has no pitch or lead along the barrel. This construction permits the follower 88 to enter the groove at substantially any relative angular position of the curling rod and the barrel. If desired, said groove 99 may be made completely circular, but to avoid a sharp shoulder in the thread or groove 71, the groove 99 is usually stopped short of a complete circle (Fig. 17). Attention is also called to the shape of the follower 88 as shown in Fig. 15. Said follower is set at a slight angle to the axis of the nut and the edges thereof are slightly rounded. This construction permits the follower to enter and contact easily throughout its travel in the groove 71, the angle of the follower being substantially an average of 70 the lead angle of the groove.

C.—Winder driving mechanism

In accordance with the invention, means are provided for imparting rotary movement to the 75 guide barrel 70 and the attached hair-engaging

devices, thereby to wind the tress about a curling rod 1 which has been inserted into the barrel and seated in the nut 90 as shown in Fig. 4. As embodied, the driving force is transmitted from a power-driven flexible shaft 100 to a ring gear 101 through a hand-controlled clutch to be herein-after described.

Referring first to the driving connections between barrel 70 and the ring gear 101, the end of barrel 70 is seated in a cylindrical socket 106 formed in one end of the cylindrical block 105. Set-screws 107 serve to fix the end of the barrel within said socket. A second cylindrical member 110 surrounds the opposite reduced end of block 105 and is fixed thereto by clamp bolts 111, 15 which bolts also serve to seat bearing retaining ring 112 against the end of block 105. The member 110 is cored to form an enlarged cylindrical shell 113 extending away from the end of block 105. The ring gear 101 is seated against a 20 shoulder formed by the annular recess 114 at the end of said shell 113. The ring gear is keyed to the shell 113 at 115, thereby to impart driving force to member 110. It will be clear that any driving motion imparted to the ring gear will 25 effect rotation of member 110 and block 105 therewith, thereby transmitting rotation to the barrel 70.

Driving force is imparted to ring gear 101 by the wide-faced pinion 118 which is connected to 30 the end of the flexible drive-shaft 100 as follows:—The pinion 118 is formed near one end of a relatively long cylindrical member 120, the opposite end face 121 of which is toothed to form the driven member of a clutch. Clutch face 121 is adapted for driving engagement with the toothed face of driving clutch member 122 formed on the end of cylindrical member 123. The opposite end of member 123 is hollowed to receive the splined end 124 of the drive-shaft 100. 40

The hereinbefore described driving mechanism is all mounted within and supported by a cylindrical supporting block 130 which forms an operating handle for the entire mechanism. Block 130 is cored at 131 to receive the clutch bushing 45 132, said bushing being fixed to the block 130 by set-screw 133. The outer end of the bushing projects from the block and is screw-threaded at 134 to connect with the threaded coupling 135 at the end of the flexible shaft housing 136. 50

The cylindrical clutch-driving member 123 is rotatable within bushing 132 and similarly the driven member 120 of the clutch is rotatably supported in the enlarged end of the bushing. The opposite reduced end 125 of member 120 is 55 journaled in a supporting plate 140, which plate is fixed to the face of block 130 by clamping bolts 141. Plate 140 also serves to receive the fixed end 82 of pilot rod 81. As shown, the end 82 of said pilot rod is tapered and has a square 60 cross-section which seats in a conforming opening in the plate 140. (Fig. 12.) This construction serves to hold the pilot rod stationary with respect to the block 130 and the other non-rotating parts of the mechanism, thereby insuring 65 that the pilot rod will serve as a fixed axis for the rotating barrel 70.

The barrel-supporting block 105, the block 110 and the ring gear 101 are all rotatably supported upon the pilot rod 81. As shown, the terminal portion 145 of said pilot rod is cylindrical and one end of said cylindrical portion rests in a bearing bushing 146 adjacent the face 98 of block 105. A ball-bearing 147 is mounted between the cylindrical portion 145 and the inner 75

cylindrical surface 148 of block 105, whereby the block 105 and its associated rotating members will turn freely about said cylindrical portion 145. Suitable retaining collars 149 and 150 are provided on the portion 145 for confining the inner race of the ball-bearing.

Additional external support is provided for carrying the rotating parts from the supporting handle block 130. A cylindrical shell 155 is fixed 5 to the surface of block 130 by screws 156. Said shell projects along and surrounds the outer surface of member 110 and forms a bearing surface therefor. A flanged annular guard 157 is screw-threaded to the end of shell 155 and overlies the 10 enlarged shoulder portion of block 110, thereby forming a substantially complete closure for the driving mechanism.

Referring now to the clutch mechanism for effecting driving connection between the clutch 20 members 121 and 122:—A floating pin 160 extends axially within the hollow interiors of members 120 and 123 and supports a helical spring 161. Said spring acts to force apart the clutching faces so that driving motion can be transmitted by the clutch only when the spring is compressed. Balls 162 are provided at either end of the spring as thrust bearings for the clutch mechanism. A clutch-actuating lever 163 is pivotally mounted exteriorly of the shell 155 and 25 an arm 164 of said lever projects through an opening of the shell and bears against a shoulder 165 on the clutch member 120. It will be clear that when the lever 163 is depressed, the member 120 will be moved axially toward member 123 to 30 effect engagement of the clutch faces and that such driving engagement will be maintained only while the lever is so depressed.

Driving force may be imparted to the flexible shaft 100 in any suitable manner and from any 40 suitable power source. In the preferred form of the invention, the flexible shaft is motivated by an electrical motor through suitable driving connections and a form adapted for beauty shop practice is illustratively disclosed in Fig. 1. As 45 shown, an electric motor 170 is mounted in a portable base housing 171 and provided with suitable lead wires 172. A winder-supporting standard 173 rises from the base and is provided with a laterally projecting arm 174 near its upper end. A vertical driving shaft 175 extends part way through the hollow standard 173 and at its lower end is drivingly connected to the motor shaft through suitable reduction gearing 176. One end of the flexible shaft 100 is coupled to 50 the upper end of vertical shaft 175 at a convenient point 177, thereby providing a convenient operating radius for the winder. A handle 178 for operating the motor switch may be conveniently located nearby.

Means are preferably provided for balancing the winding mechanism so that it will remain suspended at any desired point with respect to the head of the customer being wound. As 55 shown, the winder handle 130 is connected by a bail 180 and a cord 181 to a counter-weight 182 which may be raised and lowered within the hollow standard 173. The cord runs over suitable pulleys 183 within the arm 174. If desired, the arm 174 may be pivoted for swinging movement 60 with respect to the standard 173. It will be understood that many obvious changes in the design and construction of the stand and winder-supporting means may be made without departing 65 from the principles of the invention and the

form shown in Fig. 1 is simply illustrative of those general principles.

D.—Tape supply and winding means

As hereinbefore stated, the invention preferably embodies means for winding or lapping a flexible binding strip about the tress as it is being wound on the curling rod. In practice a very thin and porous fabric tape having a relatively loose weave has been found to be most 10 desirable for this purpose. However, other binding agents might conceivably be substituted and it is desired to cover all equivalent means such as strips of paper, flannel, wire and the like. The term "tape" as used herein will be understood 15 to broadly cover all such equivalent means. The tape may be impregnated with waving chemicals which will aid in the waving operation when moistened and steamed adjacent the hair.

In accordance with the invention, tape supply 20 means are provided which will preferably carry a substantially continuous supply of tape on the winding mechanism, i. e. enough to complete the winding of an entire head of hair. Various modified forms of tape supply means are 25 disclosed, but the simplest and present preferred form is shown in Figs. 7, 8 and 9. As embodied, a reel of tape 190 having a hollow core 191 is rotatably mounted on a stud or spindle 192. Said stud projects from a ring-shaped bracket 193 30 which surrounds and is fixed to the exterior of the barrel 70, preferably near the driving end thereof. A circular guard plate 194 is fixed to the stud 192 and forms a backing for the inner face of the reel of tape. A guard plate or bar 35 195 is loosely supported on the stud and serves to retain the outer face of the reel of tape. A nut 196 is adapted to be screwed onto the threaded end 197 of the stud to secure the plate 195 and reel of tape on the stud and to provide the 40 desired braking friction on the reel. If desired, a spring-snap connection may be provided in lieu of the threaded nut, or other suitable attaching means for the reel of tape may be substituted. It will be clear that when one reel of 45 tape is exhausted, the nut 196 and plate 195 will be removed and the empty core replaced by a fresh reel.

Suitable means for guiding the free end of the tape 200 from the reel to the hair-winding head 50 comprises a threading slot 201 in a flange 202 fixed to block 16 of the winding head. From said slot the tape passes to devices for guiding it on to the curling rod 1 where it covers and binds the hair just after same has been laid on 55 the curling rod (Fig. 5). The principal tape-guiding devices are mounted on the block forming the presser foot 10 hereinbefore described. As shown in Figs. 7 and 10, the tape is first passed over a curved guide bar 205 which extends from 60 a bracket 206 screwed to one side face of member 10. A guard finger 205a serves to hold the tape from sliding off the bar 205. A diagonal plate 207 is spaced from bar 205 to form a slot 208 through which the tape is threaded as shown 65 in Fig. 7. The tape is then brought up over the diagonal edge of plate 207 and beneath a guard finger 209 which lies slightly above the face of the plate. It will be clear that the diagonal plate 207 acts in the manner of the turner bar 70 employed generally in web-feeding practice to direct a moving web at right angles to its original course. A tape groove 210 runs around the outer portion of the presser foot and guides the tape from the turner bar 207 entirely around 75

the presser foot and on to the curling rod as shown in Figs. 5 and 18. The outer end of the presser foot is provided with a flange or guard member 211 which keeps the tape in the groove and prevents it from slipping off the end of the presser foot, and, if desired, a guard finger 212 of wire or the like may be extended across the tape groove adjacent the bottom edge of the presser foot as shown in Fig. 5.

It will be clear that the tape is fed beneath the presser foot 10 and pressed against the hair just after the latter has been laid upon the curling rod from the hair-guiding groove 41. Consequently, the tape is subjected to the pressing and stretching action of the presser foot 10 and receives the same tensioning and compression as the hair beneath it. The tape is intertwined with the hair, but is of sufficient width to overlap the curled tress entirely or substantially entirely throughout its length, so that the finished wound tress appears as shown in Fig. 2. In starting the tape around the tress, it may be introduced into the winding operation at any desired point throughout the length of the curl. Preferably, the tape is started with the hair at the scalp end of the curling rod and, as shown in Fig. 3, the tape is given a partial turn beneath the first turn of the tress as the latter is laid on the curling rod and into the winding groove 41. The tape thus acts to bind the entire curl. It catches and holds any stray short hairs which might tend to escape or spring up after the presser foot had gone by and it also completely preserves the tension and stretch imparted to the hair throughout the length of the curl. When the brush 66 is used, it holds down such stray hairs until they are completely trapped beneath the tape.

It will be understood that the interwinding and tensioning of the tape with the hair, especially at the root end of the curl, serves to produce a very firm binding action which will be maintained even if the winding operation is temporarily stopped. The completed curls are held under the tension given to them during the winding and retain said tension during the entire permanent waving process. In fact, the application of lotion, steam and/or other moisture to the taped hair during the waving process actually causes an increase in tension because the moistening of the tape makes the fabric swell and increases the binding action on the hair.

The invention preferably embodies means for severing the wound length of tape from the web after it has been wound about the tress to the desired extent. As embodied, a knife-blade 215 is mounted on the upper surface of the presser foot 10 and is adapted to shear the tape as it lies in groove 210. A fixed ledger plate 216 is mounted in groove 210 and cooperates with the blade 215 to shear the tress. The blade is normally held retracted above the web 200 as it passes over the ledger plate 216 and along the groove 210, and for this purpose the blade is pivotally mounted at 217 and a coil spring 218 holds the blade away from the ledger plate. A corrugated thumb seat 219 is provided on the back of the knife for facilitating pressing down the knife to cut the tape when desired.

The free end of the tape may be fixed to the curling rod in any desired or suitable way and in practice a simple spring clip 220 (Figs. 2 and 21) may be slipped on to the end of the tape and around the curling rod. As indicated, the winding operation is usually continued for one or more turns after all the hair has been wrapped upon

the curling rod, thereby completely enclosing the tress within a circular wrapping of tape at its upper end.

Means are preferably provided for loosely covering and holding the free end of a tress while it is being wound on a curling rod, thereby to prevent entangling and snarling the tress in the tape or rotating mechanism before it passes through the winder head. As embodied, a curved gate or guard 230 is pivotally mounted on the outer surface of the winder barrel 70 (Figs. 22, 23 and 24). Said guard 230 is spaced from the surface of the barrel so as to form a sheath for the hair between the barrel surface and the arcuate guard. One longitudinal edge of the guard is pivotally mounted on an axle 231 which extends parallel to the longitudinal axis of the barrel and spaced from the periphery of the barrel, being journaled in a plurality of pedestals 232. A helical spring 233 is wound about a portion of the length of the axle 231 and urges the guard 230 towards the surface of the barrel. An arcuate plate 234 is fixed to the surface of the barrel beneath the guard 230 and preferably forms the support for the axle-supporting pedestals 232, which may be pieces struck up therefrom. Two or more lugs 235 struck up from the edge of plate 234 provide support for the free end of the guard and form a partial closure for the hair sheath. Gate 230 may be lifted by lip 236 to permit insertion of the end of a tress which will lie freely therewithin. The gate or guard 230 is preferably slotted to expose the tress to view and the ends thereof are open to permit free passage of the tress axially of the barrel.

Operation

The operation of the present preferred embodiment hereinbefore described is briefly as follows:

The scalp of the customer is squared off into individual tresses and to each tress is tied the head of a curling rod 1, as indicated in Fig. 3. The opposite open end of one of said curling rods is then inserted into the opening 75 in the head of the winding mechanism, the presser foot 10 preferably being elevated to clear the opening. The end 83 of pilot rod 81 enters and registers with the open end of the curling rod and the pilot rod and barrel 70 are together pushed toward the scalp. The nut 90 rests loosely on the end of the curling rod, the pilot rod sliding freely through the nut. When the wall 98 at the end of the barrel meets the nut the recess 96 in the nut is forced over and onto the end of the curling rod. The follower 88 is thereby forced outwardly and seats itself in turn 99 of the helical guide groove 71. In that position, the head 4 of the curling rod extends just beyond the outer end of the presser foot 10, so that the end of the winding head lies just above the scalp of the customer.

The operator then lays the hair around the shank 3 of the curling rod (Fig. 3) beneath the brush 66 and lays the free end of the tress in the guide groove 41 of the winder. For this operation, the tension roller 48 is momentarily lifted from the guide groove to the dotted line position of Fig. 5 and is then snapped back to clamp the hair against the guide groove. Next the end of the tape 200 is pulled through groove 210 and the slack end turned around the curling rod just beneath the initial turn of the hair as shown in Fig. 3. The free end of the tress which projects through the comb teeth 65 is led along the winder barrel and encased beneath the sheath gate 230.

The tress and tape are then ready to be wound automatically upon the curling rod.

The winding operation is initiated by pressing down on the clutch lever 163, the clutch block or winder handle being gripped in the hand of the operator. As soon as the clutch engages (the shaft 100 having been set in motion by the motor switch 178), rotation is imparted to barrel 70 through the driving gears. The pilot rod 81, nut 90 and curling rod 1 remain stationary with respect to the rotating barrel and consequently the follower 88 causes the barrel to travel away from the scalp on a helical path corresponding to the groove 71.

15 The free end of the tress and the tape are carried around with the barrel and wrapped on the curling rod in a helical curl corresponding in configuration to the helical guide groove 71. Thus the thick hair near the root end of the tress is wrapped about the rod in a curl having relatively great pitch or lead, while, because of the decreasing pitch of the guide groove, the thin ends of the tress are wound closer together. As the barrel rotates about the curling rod it moves axially 20 therewith, always feeding away from the scalp end. The pilot rod 81 slides axially within the curling rod, but does not rotate and thus prevents any rotary movement being imparted to the curling rod, so that twisting or pulling of the hair at the scalp is impossible. As the pilot rod withdraws from the interior of the curling rod, the nut 90 remains seated on the end of the curling rod, being frictionally held there by the gripping action of the dog 97 on the latch 89. When 25 the follower 88 reaches the final, circular turn 80 in the groove 71, the winder may be permitted to rotate as many times as desired and thereby make several concentric turns of hair and/or tape at the end of the curl.

30 When the winding operation has been completed, the tape is severed by the knife 215. The nut is readily disengaged from the end of the curling rod by simply holding the curling rod and pulling the winder away from it. The nut cannot fall out of the barrel 70 because of the restricted opening at the head end thereof. As 35 soon as the winder has been wholly withdrawn from the curling rod, a tape clip 220 is pushed on the curling rod at the end of the tape and that curl is completely wound and taped and ready 40 for steaming as shown in Fig. 2. Thereafter, the winder is successively applied to the other curling rods on the customer's head and the respective tresses wound and bound upon them.

45 During the winding of a curl, the operator has merely to grip the handle 130 steadily and keep the clutch lever 163 depressed. The winder can rotate only under the conscious control of the operator. If the operator should inadvertently let go of the handle, the clutch would instantly 50 disengage and the winding movement cease. Even if the clutch should jam and fail to disengage, the continued rotation of the winder could only cause it to back away from the scalp and eventually disengage itself from the curling rod. 55 During such movement the winder could not impart any turning or twisting to the curling rod because of the locking action of the pilot. The winder and curling rod can be completely disengaged at any time by simply pulling nut 90 off 60 the end of the rod 1. The counter-balancing action of the weight 182 and suspending means 181 causes the winder to hang steadily in any position. Consequently, even if the operator should let go of the winder when it is attached to a curling rod, no effect is felt by the customer because 65

the winder hangs perfectly steadily in the position last imparted to it.

As will be clear from the drawings, the construction of the winding and guiding means is such that a perfectly flat and partially overlapping curl of decreasing pitch is imparted to the hair. This type of curl is considered ideal in hairdressing and is exceedingly difficult to produce even by the most skilled hand-winding. Furthermore, said type of curl requires great 10 manual strength and skilled operators cannot consistently produce such curls over any appreciable period of time. With the automatic winding mechanism hereinbefore described, every curl is uniformly perfect. It will be understood, of 15 course, that different forms of guide means may be utilized in winding hair so as to produce curls of different configuration and the invention is not limited to the exact curl form disclosed, but said form represents the present preferred practice 20 in hairdressing. Obviously, guide grooves and barrels having guides of any desired shape can be substituted for that shown herein.

The winding mechanism is capable of considerable flexibility in its operation over and 25 above the usual or standard winding action hereinbefore described. For example, it is frequently desirable to give the ends of the tresses a very tightly wound and substantially concentric ringlet curl, especially when working with relatively 30 short hair. This may be done with the automatic winder as follows:—When a few initial turns of the short tress about the curling rod have been made, the winder may be stopped 35 momentarily and the nut 90 disengaged from the end of the curling rod by pulling the winder very slightly away from the curling rod. This operation causes the follower 88 to collapse into the groove 91 of the nut and the winder barrel then will have a purely circular motion about 40 the curling rod. The remainder of the curl may then be formed independently of the configuration of the guide groove 71, the pitch being entirely dependent upon the rate at which the operator moves the barrel axially along the curling rod. Thus any desired portion of the end 45 of the curl may be made wholly circular or with as much or as little pitch as selected. This operation is especially helpful in curling very short hair and it is possible to make a ringlet curl on 50 a tress less than an inch long and on such tresses having only a relatively few hairs, the curl being formed in a complete ringlet right against the scalp. It will be clear that the pilot rod 81 acts to restrain rotation of the curling rod 1 even 55 when the nut is disengaged from the end of the curling rod, so that the safety action of the pilot rod is exerted even when the guiding action of the guide groove 71 is not exerted.

The winding operation may be started at any 60 point in the length of the tress. Thus if the customer desires a curl only in the ends of her hair, the end of the curling rod may be tied to the tress at the selected point and the winding started there.

In winding a very short tress such as one less than an inch long, for example, the end of the tress need not be laid under the roller 48 in the guide groove 41, but may be placed under 70 the presser foot 11 and brush 66. These members act to tension and compress the short hair and said hair may be quickly wound around the end of the rod and taped, preferably without engaging the nut 90 at the end of the rod, there- 75

by producing a complete ringlet in the tress or wisp of hair.

In the operation of the winding mechanism, it should be noted that the hair is under a continuous and uniform tension during the winding operation. This feature is of great importance and constitutes an advance over the hand winding method. In hand winding the hair is alternately subjected to a vigorous stretch by the thumb and then partially released as the hand is brought back for a fresh grip. Hand winding thus subjects the hair to an intermittent stretching and loosening action and the stretch is not maintained throughout the entire curl. This feature of my invention is of great importance especially in the winding of weak hair which breaks easily, such as bleached hair or dried out and overheated hair. The amount of breakage on such hair is practically nil when it is curled by my winding mechanism.

Modifications

Several modifications of different features of the winding mechanism are disclosed in the drawings, said modified forms relating principally to the winder-guiding means and to the tape-supply means.

Referring first to modified forms of winder-guiding mechanism, one such form is shown in Figs. 28, 29, 30 and 32. The modifications consist primarily in providing the helical guide groove within the bore of the curling rod itself. As embodied, a curling rod 300 is formed with the same general exterior as that of the curling rod 1. However, the interior of bore 301 of the curling rod is cylindrical except for an inwardly projecting key or spline 302 which extends along part of the length of said bore and serves to cooperate with the helically-grooved pilot rod 305 hereinafter described.

As shown in Figs. 28 and 29, a cylindrical pilot rod 305 is adapted to fit within the bore 301 of the curling rod 300. The pilot rod is disposed axially within the cylindrical winder barrel 306 and is held stationary with respect thereto so as to form a fixed axis about which the winder barrel rotates. The fixed end of the pilot rod 305 is engaged within the clutch body and handle 155 and said construction may be substantially identical with that hereinbefore described in connection with the preferred form.

A helical guide groove 307 is cut in the cylindrical surface of the pilot rod 305, said groove extending throughout that portion of the rod which enters the bore of curling rod 300. The helical groove 307 is preferably similar in configuration to that of the groove 71 in the preferred form. A keyway 308 is cut in the cylindrical surface of the grooved portion of the pilot rod 305 and provides a seat for the key or spline 302 as shown in Fig. 32. It will be clear that this construction locks the curling rod to the pilot rod and prevents relative rotation between said members during the winding operation.

The embodied means for effecting winding cooperation between the curling rod 300, the grooved pilot rod 305 and the rotatable winder barrel 306 comprises a spring-urged follower 310 which is mounted to rotate with the winder barrel 306 while engaging the helical groove 307. The plunger 310 is mounted in and extends radially through the cylindrical nut 311. Said nut is bored at 312 to fit rotatably on the exterior cylindrical surface of pilot rod 305. The nut is provided with a reduced extension 313 which is counter-

bored at 314 to receive the open end of the cylindrical curling rod 300.

The nut 311 is rotatable about the open end of the curling rod, but is restrained from axial movement with respect thereto during the winding operation by a ball clutch connection. As embodied, a shallow circular groove 315 is provided around the end of the curling rod about midway of the portion which is received in the recess 314 of the nut. A ball 316 is suitably housed in the end portion 313 of the nut and is adapted to engage within said groove 315 on the curling rod. A curved leaf spring 317 is fixed to the portion 313 of the nut and serves to force the ball 316 into engagement with the groove 315.

The follower 310 and nut 311 are mounted for axial movement with respect to the rotating barrel 306 as they rotate therewith. As embodied, an open guide slot 320 extends axially throughout the length of the barrel, said guide slot being equivalent in length to the grooved portion of the pilot rod 305. The nut 311 is provided with a radially-extending key or shoulder 321 which is adapted to fit slidably within the slot 320 and lie substantially flush with the outer surface of the barrel. Said key 321 is fixed to the surface of the nut as by a set-screw 322. It will be clear that this construction causes the nut to rotate with the barrel and at the same time permits axial movement of the nut along the barrel as the winder is fed helically away from the end of the curling rod to which the nut is clamped by the ball clutch 316.

The follower 310 is adapted for radial movement into and out of the guide groove 307 and is normally urged into the groove by a helical spring 324 which surrounds a portion of the follower shank within the radial chamber 325 in the nut. A knurled head 326 is preferably attached to the outer end of the plunger for easy manipulation thereof.

In the operation of the above-described winder-guiding means, the winder head 16 and winder barrel 306 are placed over the curling rod and the pilot rod 305 inserted into the open end thereof. When the winder has been shoved home, the end of the curling rod will enter the recess 314 on the nut 311 and the ball clutch 316 will engage the groove 315 on the curling rod. The follower 310 normally rests in the groove 307 and accordingly the device is then ready for winding rotation, as shown in Fig. 28. The actual winding operation, including the application of power and the control thereof, will take place substantially in the same manner as already described in connection with the preferred embodiment.

If it is desired to disengage the follower from the guiding groove at any selected position in the length thereof, this may be done by pulling out the plunger head 326 and sliding the nut off the end of the curling rod.

Another modification of the invention (Fig. 33) provides for selective winding of relatively short hair, preferably on relatively short curling rods 330. The general features of the winder shown in Fig. 33 are the same as those disclosed herein as the preferred embodiment of the invention. However, this modification provides for winding hair on a relatively short rod in the portion of the guide groove 71 having the reduced pitch, so that the ends of the curl will be wound tightly.

More specifically, means are provided for connecting the follower nut 90 to the end of a short curling rod at an intermediate portion of the winder barrel, so that the winding operation may

be initiated at an intermediate point of the guide groove 71 thereby to wind the relatively short tress in a curl of relatively small pitch or lead. As embodied, a pin 332 is mounted for radial movement through an opening 333 in the wall of barrel 70, said pin being movable into the interior of the barrel to act as a stop for the nut 90. As shown, the pin is carried on the end of a flat spring 334 the other end of which is fixed to the exterior of the barrel, so that the pin is normally retracted to the extent that its inner end lies flush with or beneath the inner surface of the barrel 70. A device for forcing the end of the pin into the interior of the barrel and into the position shown in Figs. 33 and 34 comprises an eccentric actuating disc 335 which bears against the free end of the spring 334. Said disc is rotatably mounted on a lip preferably struck up from the plate 234 and is provided with a small actuating handle 336. When it is desired to initiate the curling operation at an intermediate point of the guide groove 71, the nut 90 is stopped by the blocking action of pin 332 and the relatively short curling rod 330 may then be seated in the nut at said intermediate point. In normal operation on longer hair, longer curling rods 1 will be used and the pin 332 will be maintained retracted by moving the handle 336 so that it lies parallel to the axis of the barrel. It will be understood that more than one such stop pin may be provided at different points along the barrel, or if desired, the pin could be slideable along the barrel and insertable at a plurality of positions.

Referring now to modified forms of tape-supply means, one such form is shown in detail in Figs. 4 and 22 to 27 inclusive. Said modified form of tape-supply means comprises the provision of a bale or package 340 of tape folded in plicated form (Fig. 27). Said bale of tape is preferably formed so as to be mounted in an arcuate casing on the exterior of the winder barrel 70. Accordingly, the bale of tape may be attached to a flexible backing sheet 341 along one face of the plicated bale. The attachment of said backing sheet 341 may be made by a relatively light adhesive so that the tape will cling as a bale to the face of the backing sheet yet a slight pull will disengage a length of the tape from the remainder of the bale.

The bale of tape 340 is adapted to be mounted in an arcuate container on the outer surface of the barrel 70 of the winder. As embodied, a curved sheet metal base 343 is fixed to the outer surface of the winder barrel. The base 343 is preferably hemi-cylindrical and extends substantially the length of the barrel, thereby providing as much space as possible for packaging of the tape. One end of the base is provided with an ear 344 which is clamped under the member 105 at the driven end of the winder barrel (Fig. 4). The other end of the base is fastened to the winder barrel by screws or rivets 345. A plurality of tongues 346 are struck up from the periphery of the curved portion 343 of the base and said tongues provide a seat for the edges of the backing sheet 341 when same is curved about the base, as shown in Figs. 23 and 24.

A suitable curved cover 347 is hingedly connected to one edge of the base plate 344, hinged lugs 348 being struck up from the radial flange 349 of the base plate for this purpose. The opposite side of the base plate is provided with another radial flange 350 which cooperates with the curved cover 347 to make a complete closure

for the tape package. The ends of the cover 347 are closed by flanges 351 and a suitable closing action is provided by the spring lip 352 which cooperates with the outer edge of flange 350.

The tape is fed from the plicated bale 340 as shown in Fig. 18. A feed slot 355 is provided in the flange 350 of the container base plates 343 and the tape passes through said slot and into the guide opening 208 of the tape-guiding device hereinbefore described.

Another modified form of tape-supply means is shown in Figs. 28, 30 and 31. In said modification, one or more rolls of tape 360 are removably journaled in a housing 361 which forms an integral part of the winder mechanism and is positioned between the winder barrel and the control handle 155. As shown, the tape housing 361 is provided in connection with the winder driving device embodying the helically grooved pilot rod. However, said tape-supply means may also be used with the preferred form of the winder-guiding mechanism, shown in Fig. 4, etc.

The tape roll housing 361 comprises a rectangular block having an axial bore 362 which surrounds and is rotatable with respect to the cylindrical end portion 363 of the pilot rod 305. The end of winder barrel 306 is fixed to the reduced circular end 364 of block 361 by the set-screws 365 and a bearing bushing 367 is provided at the end of the bore 362 for supporting the block 30 on the pilot rod.

Block 361 is hollowed out on either side of the central bored portion to provide two parallel rectangular chambers 370 for receiving the circular rolls of tape 360. Said rolls of tape are preferably removably supported within the chambers 370 and are adapted to rotate therewithin. As embodied, a roll of tape is mounted on a hollow spool or spindle 371 and the spool is journaled to rotate within a U-shaped spring clip 372. Said clip is provided with bosses 373 which project into the bore of the spool and act as trunnions therefor. The clip 372 is slideable within grooves 374 formed in the sides of the chambers 370 and bosses 375 are provided on either side of the spring clip for seating the same in suitable recesses within said grooves 374. Preferably the roll of tape 360 is assembled in a clip 372 and the assembled clip and roll are then slid into a chamber 370. The flange ends 371 of the clip may be squeezed together to facilitate entry and removal of the clip and roll.

As shown in Fig. 30, the free end 200 of the tape from roll 360 is fed tangentially out of the chamber 370 and to the guiding and winding mechanism hereinbefore described. The double chamber arrangement permits carrying of an extra roll of tape without stopping to reload in the middle of a winding operation. The spring clips 372 not only facilitate loading of the tape but provide a friction braking on the sides of the rotating roll.

The invention in its broader aspects is not limited to the specific mechanisms shown and described but departures may be made therefrom within the scope of the accompanying claims without departing from the principles of the invention and without sacrificing its chief advantages.

What I claim is:

1. Hair winding mechanism including in combination a mandrel attachable to a tress on a head, a curl winding device for winding the tress around the mandrel and means movable with the

- winding device during the winding operation for preventing turning of the mandrel.
2. Hair winding mechanism including in combination a mandrel attachable to a tress on a head, a curl winding device for winding the trees around the mandrel and means movable axially of the mandrel for preventing turning thereof during the winding operation.
3. Hair winding mechanism including in combination a hair-engaging device, means for moving said device along and about a mandrel in a helical path to wind hair thereon, and means moving with the winding device for restraining the mandrel from turning with the winding device during the winding movement thereof.
4. Hair winding mechanism including in combination a mandrel, means for attaching the mandrel to a tress near the scalp, hair-engaging devices, power-driven means for traveling said devices in a predetermined helical path to wind the tress along and about said mandrel and means for restraining the mandrel from being moved by said devices during the travel thereof.
5. Hair winding mechanism including in combination a cylindrical mandrel having a non-circular portion, means for attaching said mandrel to a tress near the scalp, means for winding the tress around the mandrel in a helical curl, and means engaging said non-circular portion of the mandrel to prevent movement from being imparted thereto by the winding means.
6. Hair winding mechanism including in combination a tubular mandrel, means for winding a tress of hair in a helical curl upon the mandrel, and means engaging the interior of the mandrel to prevent the winding means from imparting movement to the mandrel.
7. The method of winding hair for permanent waving which comprises winding a tress around a mandrel and simultaneously feeding tape from a substantially continuous supply, wrapping said tape around the hair and mandrel and severing the tape from said supply when the tress has been wound.
8. The method of winding hair for permanent waving which comprises successively winding a plurality of tresses on a human head around individual mandrels attached to the various tresses, feeding tape from a substantially continuous supply and wrapping said tape around the tress and mandrel being wound, severing the tape when said tress has been wound, winding another tress and wrapping it with tape from said supply.
9. The method of winding hair for permanent waving which comprises winding a tress around a mandrel in a coil of predetermined helical configuration and simultaneously feeding tape from a substantially continuous supply and wrapping said tape around the hair and mandrel.
10. The method of winding hair for permanent waving which comprises winding a tress around a mandrel and simultaneously feeding tape from a substantially continuous supply and wrapping said tape around the hair and mandrel, severing the tape from said supply when the tress has been wound and fastening the severed tape to the mandrel.
11. A mechanism for winding hair for permanent waving including in combination a mandrel, power-driven means for winding a tress about the mandrel, means for supporting a substantially continuous supply of tape, and means for feeding tape from said supply to the hair winding means.
12. A mechanism for winding hair for permanent waving including in combination a mandrel, a power-driven device for winding hair thereupon, means carried by said device for supporting a substantially continuous supply of tape, and means for winding said tape about the mandrel. 5
13. A mechanism for winding hair for permanent waving including in combination means for winding a tress in a curl, tape-supply means and tape-cutting means. 10
14. As an article of manufacture, a hair-winding device having tape-cutting means mounted thereon means for supporting a roll of tape and guide means for leading the tape from the roll past the tape-cutting means. 15
15. A mechanism for winding hair for permanent waving including in combination a mandrel attachable to hair on the human head, means for winding a tress around the mandrel including hair-engaging devices and means for guiding said devices in a predetermined path with respect to the mandrel comprising a tubular member having a guide on its interior. 20
16. A mechanism for winding hair for permanent waving including in combination a mandrel attachable to hair on the human head, means for winding a tress around the mandrel including hair-engaging devices and means for guiding said devices in a predetermined path with respect to the mandrel comprising a tubular member having a guide groove on its interior. 25
17. A mechanism for winding hair for permanent waving including in combination a mandrel attachable to hair on the human head, means for winding a tress around the mandrel including hair-engaging devices and means for guiding said devices in a predetermined path with respect to the mandrel comprising a tubular member having a helical guide on its interior. 30
18. A mechanism for winding hair for permanent waving including in combination a mandrel attachable to hair on the human head, means for winding a tress around the mandrel including hair-engaging devices and means for guiding said devices in a predetermined path with respect to the mandrel comprising a tubular member having a helical guide groove on its interior. 40
19. A hair-winding mechanism adapted to contact with a curling rod and including in combination a tress-engaging device movable along and about the curling rod to wind the tress thereon, means for rotatably supporting a roll of tape with its axis transverse to the path of travel of the tress-engaging device and means for guiding tape from the roll to said device to wind the tape with the hair about the rod. 50
20. A hair-winding mechanism adapted to contact with a curling rod and including in combination a tress-engaging device rotatable along and about the curling rod to wind the tress thereon, means for rotatably supporting a roll of tape with its axis transverse to that of the curling rod and means for guiding tape from the roll to the tress-engaging device to wind the tape with the hair about the rod. 60
21. A hair-winding mechanism adapted to contact with a curling rod and including in combination a tress-engaging device rotatable along and about the curling rod to wind the tress thereon, means for supporting a roll of tape with its axis transverse to the axis of the curling rod and rotating with reference to the tress-engaging device, and means for guiding tape from the roll to the tress-engaging device to wind the tape with the hair about the rod. 65
22. A hair-winding mechanism including in 70

combination a hair-engaging device movable axially and rotatably to wind a tress helically on a curling rod and means for rotatably supporting a roll of tape on said device with the axis of the roll transverse to that of the device.

5. 23. A hair-winding mechanism including in combination a hair-engaging device movable axially and rotatably to wind a tress helically on a curling rod and means for rotatably supporting a 10 roll of tape on said device with the axis of the roll transverse to that of the device and rotating with the device.

10. 24. A hair-winding mechanism including in

combination a curling rod having means at one end thereof for attachment to a lock of hair and for thereby holding the end of a tape to be wound around said lock of hair, a hair and tape-winding member including a tubular body provided with a 5 winding head, a tape roll supporting member having its axis substantially at right angles to the length of the tubular body and guide means for the tape to the winding head, said winding head constructed to feed, in operation, the winding member rearwardly from the hair and tape-holding member of the mandrel.

VIRGINIO JEAN GENTILE.
